HANDLE CONTROL FOR SUCTION CLEANERS

Filed July 8, 1948

UNITED STATES PATENT OFFICE

2,576,727

HANDLE CONTROL FOR SUCTION CLEANERS

Louis E. Segesman, Canton, Ohio, assignor to The Hoover Company, North Canton, Ohio, a corporation of Ohio

Application July 8, 1948, Serial No. 37,705

4 Claims. (Cl. 306—13)

1

The present invention relates to suction cleaners and more particularly to a new and improved handle control in a suction cleaner.

It is an object of the invention to provide a new and improved suction cleaner. Another object is to provide a simple and durable handle control. A further object is to provide a handle control permitting free movement of the handle in each of the working range adjustments and resiliently prevent movement of the handle into another adjusted working range. Other objects and advantages of the invention will be apparent from the following specification and drawings wherein:

Figure 1 is a side elevational view of the invention;

Figure 2 is a perspective view of the lever means attached to the cleaner handle; and

Figure 3 is a section along the line 3—3 of Figure 1.

The invention herein disclosed comprises a suction cleaner body 10 supported on front and rear wheels 11 and 12 respectively, and having a nozzle 13, a fan chamber 14 discharging into a bag 15 and a motor housing 16. The body 10 is propelled over the surface being cleaned by a handle 17 provided with a pair of bail arms 18, only one of which is shown, disposed on opposite sides of the motor housing 16 and are pivotally mounted on a rod 19 supported in the housing 16. An unshown torsion spring is disposed about the rod 19 to counterbalance the weight of the handle 17.

The handle control mechanism comprises a member 20 secured to the housing 16 by rivets 21 and is provided with a flange 22 having spaced seats or recesses 23, 24 and 25 representing different handle positions defined by projections 26, 27, 28 and 29.

A lever 31 has a part formed in substantially U-shape to provide walls 33 and 34 which are disposed on opposite sides of the bail arm 18 and are pivotally mounted thereon by a rivet 35. A portion 36 is cut out of the U-shaped part of the lever 31 and forms a continuation of the wall 33 and has rigidly mounted therein a pin 37 on which is rotatably mounted a detent roller 38 adapted to move between the projections 26, 27, 28 and 29. A stop 40 projects laterally from the lever wall 33 and abuts the edge 41 of the bail arm 18 to limit counterclockwise movement of the lever, as viewed in Figure 1, and prevent the detent 38 from engaging the surface of the recessed seats 23, 24 and 25. An arm 42 also

2

extends from the lever wall 33 to receive one end 43 of a spring 44 disposed about the rod 19 between the member 20 and the bail arm 18, and the opposite end 45 of the spring is secured to the bail arm 18. The spring 44 moves the lever 31 in a counterclockwise direction, as viewed in Figure 1, to urge the stop 40 against the edge 41 of the bail arm 18 and resiliently prevent the roller detent 38 from passing over the projections 27 and 28 unless a force is exerted on the handle to move the latter to another adjusted working range.

In operation, if the roller detent 38 is in the seat 23 the handle 17 is held in vertical position with the roller detent 38 abutting the projections 26 and 27. If it is desired to move the handle into the working range defined between the projections 27 and 28, the operator exerts a rearward force on the handle whereupon the roller detent 38 rides on the projection 27 to pivot the lever 31 clockwise against the force of the spring 44. After the roller detent 38 passes the projection 27, the spring 44 rotates the lever 31 counterclockwise into the seat 24, and moves the stop 40 to abut the edge 41 of the bail arm 18 to maintain the roller detent 38 out of contact with the recessed surface of the seat 24. In maintaining the roller detent 38 out of contact with the surface of the recessed seat 24 the handle moves freely in the working range between the projections 27 and 28.

If it is desired to move the handle 17 to the lower range of adjustment defined between the projections 28 and 29 a force is exerted on the handle to cause the detent 38 to ride over the projection 28 into the seat 25 but out of contact with the surface thereof. In order to raise the handle 17, an upward force is exerted thereon to move the roller detent 38 into the desired working range. The projections 26, 29 are contoured to limit respectively the high and low positions of the handle 17.

While I have shown and described but a single modification of my invention, it is to be understood that this modification is to be taken as illustrative only and not in a limiting sense. I do not wish to be limited to the particular structures shown and described, but to include all equivalent variations thereof except as limited by the scope of the claims.

I claim:

1. In a suction cleaner, a body, a handle pivotally mounted on said body, means having spaced recessed portions defined by projections

representing different extents of adjusted handle movement between adjacent projections, lever means having detent means engageable with said projections to limit the range of adjusted handle movement with respect to said body, said projections and lever means being supported on said handle and body, stop means to prevent engagement of said detent means with the surface of said recessed portions between adjacent projections during movement of said handle between such projections, and resilient means engaging said lever means to resiliently prevent movement of said detent means beyond said projections unless a force is exerted on said handle to move said detent means over a projection into another range of adjusted handle position.

2. In a suction cleaner, a body, a handle pivotally mounted on said body, means on said body having spaced recessed portions defined by projections representing different extents of adjusted handle movement between adjacent projections, lever means pivotally mounted on said handle and having detent means engageable with said projections to limit the range of adjusted handle movement with respect to said body, stop means on said lever means engaging said handle to prevent engagement of said detent means with said recessed portions, and resilient means engaging said lever means to resiliently prevent movement of said detent means beyond said projections unless a force is exerted on said handle to move said detent means over a projection into another range of adjusted handle position.

3. In a suction cleaner, a body, a rigid handle pivotally mounted on said body, means on said body having spaced recessed portions defined by projections representing different extents of adjusted handle movement between adjacent projections, lever means having portions on opposite sides of said handle for pivotal connection thereto, detent means on said lever means engageable with said projections to limit the range

of adjusted handle movement with respect to said body, stop means on said lever means engageable with said handle to limit movement of said detent means in one direction, and resilient means engaging said lever means to prevent movement of said detent means in another direction beyond said projections unless a force is exerted on said rigid handle, said handle due to its rigid structure transmitting said applied force to said lever means to move said detent means over a projection into another range of adjusted handle position.

4. In a suction cleaner, a body, a handle pivotally mounted on said body, means on said body having spaced recessed portions defined by projections representing different extents of adjusted handle movement between adjacent projections, lever means having portions on opposite sides of said handle for pivotal connection thereto, detent means on said lever means engageable with said projections to limit the range of adjusted handle movement with respect to said body, stop means on said lever means engaging said handle to prevent said detent means from engaging said recessed portions, and resilient means arranged about the handle pivot and engaging said lever means to resiliently prevent movement of said detent means beyond said projections unless a force is exerted on said handle to move said detent means over a projection into another range of adjusted handle position.

LOUIS E. SEGESMAN.
